ABSTRACT OF THE DISCLOSURE

The knot forming and support device of a pretied necktie is formed with a front chamber in which the necktie fabric can be deposited to form a dimple under the knot at the option of the wearer. The fabric itself is also provided with four mounting holes as contrasted with the usual two holes, the additional two holes enabling the necktie to be impaled over a clamp arm abutment post on the device so as to fix and to stabilize the formed knot against becoming loosened thereafter.

This invention relates to neckwear and more particularly to neckties of the pretied types provided with clip or clamp means on a knot forming and support member for releasably attaching the necktie to a collar neckband.

The general arrangement of such pretied neckties is described in our U.S. Pat. Nos. 2,798,226; 3,220,015 and 3,237,208.

In this application we disclose a forming and support member of novel construction provided with a spring plate and clamp arm essentially as shown in our Pat. No. 3,220,015. However, in this application we have provided a body member having a pronounced front cavity or chamber for the following purpose: It is well known that a front dimple under the knot is desirable. With our front chamber forming member we can optionally produce such a dimple, as desired. All the wearer need do is push the tie fabric behind the knot, into the chamber where it will be retained. This produces the desired dimple.

In this application we also disclose improved assembly of the necktie on the forming member in that the usual rear folded sections of the formed knot are themselves mounted or impaled on the rear post which serves as an abutment for the clamp arm as described in the above patents. By thus impaling the knot rear sections, the knot structure is considerably stabilized and any tendency to become untied is minimized.

The invention will be further understood from the following description and drawings wherein:

FIG. 1 is a fragmentary side view showing, in partly broken away form, the finished pretied necktie as it is worn;

FIG. 2 is an enlarged front elevational view of the knot forming and support member with the clamp arm in the downward, locking position;

FIG. 3 is a rear elevational view thereof with the clamp arm in the downward, locking position;

FIG. 4 is a bottom plan view thereof;

FIG. 5 is a cross-sectional view as taken along the line 5—5 of FIG. 2;

FIG. 6 is a fragmentary rear perspective view of the finished pretied necktie as it is worn; and

FIG. 7 is a fragmentary plan view of the necktie itself before it is applied to the knot forming and support member.

In the drawings the reference numeral 10 generally designates the pretied or preknotted tie which is illus-

2

trated as attached to the band 11 of a shirt collar 12 on a wearer W. The knot K of the tie 10 is supported and releasably attached to the neckband 11 by a tie or knot forming and support device 13 constructed according to the instant invention. The device comprises a winged knot forming and body member 14, a spring plate 16, and a clamp arm 17.

The improved knot forming and support device is made up of body member 14 which is advantageously of a molded, somewhat resilient plastic material like polyethylene or indeed of any conventional material whether metal or pressed fiber board. It is of approximately triangular configuration with a bottom, medially located, downwardly rearwardly inclined apex section 18 and a pair of laterally extending rearwardly directed wings 19 symmetrical to the vertical medial axis of the body member 14. The side edges 20 of member 14 converge arcuately downwardly to the apex section 18.

A short front wall section 21 bridges the wings 19. Immediately below wall 21 is formed a somewhat key-hole shaped opening forming a front chamber 22 having a top wall 23, a recessed arcuate rear wall 24 and arcuate side walls 25, all of these elements defining the front chamber 22 which is of approximately tubular form.

Spring plate 16 and clamp arm 17 are essentially of conventional construction, being described in our prior Pat. Nos. 3,237,208 and 3,220,015. Further, the knot forming and support device includes the abutment post 26 which is provided with an adjustable head 27 for varying the tilt of the tie as worn, all as explained in the above mentioned patent.

This invention also includes the special mounting of the necktie itself which is illustrated in FIGS. 6 and 7. Tie 30 is of conventional length for these pre-tied neckties, and is provided with four mounting holes as illustrated. These holes are formed approximately centrally of the necktie. Holes 31 and 32 are smaller, are closer to adjacent edge 33, and may be 2½ inches apart. Holes 34 and 35 are slightly larger, are further transversely inward, and may be 3⅓ inches apart. Thus holes 34 and 35 are longitudinally outward of holes 31 and 32.

Necktie 30 is draped around the knot forming and support device in a well known manner, except that the holes 31 and 32 are utilized to firmly impale and fix the rear folds 36 and 37 in place so as to not only eliminate the need for stitching such folds in place, but to further enhance the stability of the tied necktie, practically eliminating any likelihood of the necktie becoming loose thereafter.

Briefly, hole 34 is first mounted on clamp arm 17, the hole 35 being likewise so mounted as the tying proceeds. In this manner, the rear folds 36 and 37 are firmly grasped at their tops, this procedure being known. However, during the tying process, it will be found that fold 36 has hole 31 formed therethrough, which hole 31 is disposed so as to be mounted over post 26. Likewise, rear fold 37 has hole 32 formed therethrough which is also mounted on post 26. This novel mounting of holes 31 and 32 on post 26 provides the stability above mentioned. Of course, the fastening disk 40 is applied over post 26 as described in Pat. No. 3,220,015, and post head 27 is screwed into post 26 as also set forth in said prior patent.

The front chamber 22 is utilized as follows: After the necktie is fully tied, ready for use, the wearer clamps it on neckband 11 as is well understood. Now, should the wearer desire to form a dimple under the knot K, he will hold the knot in one hand while pushing the fabric material immediately below, or the fabric material adjacent the chamber 22, into said chamber with his thumb or other finger, and at the same time pulling the long end of the necktie with his other hand. This will

firmly deposit the fabric material into chamber 22 to produce the desired dimple.

We have shown a preferred embodiment of our invention but it is obvious that numerous changes and omissions may be made therein without departing from its spirit.

What is claimed is:

1. A necktie knot forming and support device comprising a pair of wings around which a necktie fabric may be draped and connected, a central front section between said wings, and a front chamber formed in said central front section whereby a portion of the necktie fabric can be inserted therein to form a front dimple in the fabric under the knot, said front chamber being tubular and being formed with a bottom opening.

2. A necktie knot forming and support device according to claim 1 and wherein said front chamber is formed with a flat top wall one side of which defines the top of said chamber, and a clamp arm and spring mechanism connected to said pair of wings for clamping said device to the neckband of a shirt, said spring mechanism being secured to the other side of said flat top wall.

3. A necktie knot forming and support device according to claim 2 and including an abutment post for said

clamp arm, said post being disposed at the lower end of said spring mechanism, and a necktie fabric formed into a knot around said device and having at least one length suspended therefrom, said necktie fabric having two holes preformed therein which are received by said clamp arm, and a further two preformed holes which are received by said post, and fabric locking means on said post.

4. In a necktie knot and forming device, having a clamp arm and a post, a necktie fabric connected to and suspended from said device, said necktie fabric having two holes preformed therein which are received by said clamp arm, and a further two holes preformed in said fabric which are received by said post, said further two holes being disposed transversely inwardly of the first named two holes, and also being disposed longitudinally outwardly of said first named two holes.
